UNITED STATES PATENT OFFICE

CHARLES F. HUMPHREYS AND J. CLARENCE McCARTHY, OF LANCASTER, PENNSYLVANIA, ASSIGNORS TO ARMSTRONG CORK COMPANY, OF LANCASTER, PENNSYLVANIA, A CORPORATION OF PENNSYLVANIA

PRINTING MARBLEIZED PATTERNS ON FLOOR COVERINGS

Original application filed August 12, 1926, Serial No. 128,870. Divided and this application filed October 30, 1929. Serial No. 403,481.

This application is a division of our application, Serial No. 128,870, filed August 12, 1926.

In the printing of linoleum and other hard surface floor coverings, complementary blocks are employed for successively applying different colored paints to the floor covering to produce the finished pattern. These blocks, in order to properly apply the paint, have a finely subdivided or peg like printing surface. A solid surface is ineffective because it does not allow the paint to spread properly, and when it is lifted from the goods, it tends to suck the paint up with it, mutilating the pattern and further preventing even distribution of the paint. Solid printing surfaces are, therefore, entirely inconsistent with good practice, and are nowhere used.

In the production of marble effects in printed floor coverings, colored lines of one or more colors are printed on the surface of the floor covering after a ground color has been applied. These lines are crooked and curved, resembling worms, rather than marble, and they are exactly duplicated with each impression of the printing block, each line being regularly repeated at regular intervals in the product.

According to the present invention, these lines are mutilated and blended together and blended into the ground coat of paint, whereby an artistic marbleized effect is procured, wherein exact repeats are avoided and a truly mottled appearance obtained.

The invention may be readily understood by reference to the accompanying drawings, in which

Figure 1 represents diagrammatically a longitudinal section through a block printing machine.

Figure 2 represents a portion of the printing surface of each of the blocks shown in Figure 1.

Figure 3 shows a portion of the printed surface up to the point where the curved lines are printed on the floor covering.

Figure 4 shows a portion of the printed surface after the first step of our process.

Figure 5 shows a portion of the printed surface after the final step of our process.

In the drawings, 2 designates the bed of a printing machine, 3 the web of material being printed, 4 is the first printing head, 5 the second, 6 the third, 7 the fourth, 8 the fifth and 9 is the sixth printing head. There may be fewer or more printing heads, the number illustrated being arbitrary and being sufficient to produce a floor covering according to our method.

Our invention will be described in connection with a floor covering having a contrasting tile design, wherein one set of square or tiles has a marbleized effect produced therein, but it will be obvious that this is only by way of illustration, and that the marbleized effect can be procured over any part of the surface of the floor covering, as may be desired.

In the printing of linoleum, the web 3 is intermittently moved along the bed of the machine, and while the web is stationary, the printing blocks are brought down against the surfaces thereof. The printing head or block 4 has printing surfaces 4a thereon, which apply the ground color or paint for one set of tiles or blocks, such as the squares 10 in the finished product in which the marbleized appearance is procured.

The next printing head, 5, applies a flat color to the other set of squares, 11, this block having printing surfaces 5a thereon so positioned as not to overlap the pattern produced by head 4. In this particular illustration, these two blocks 4 and 5 will coat the entire surface of the material as it moves thereunder, covering the entire surface with the contrasting squares 10 and 11. In making a more intricate pattern, more blocks are used. The printing surfaces of the two blocks are of the usual sawed or peg-like form, being finely subdivided to secure an even spread of the paint.

The succeeding printing block 6 has a printing surface 6a adapted to print crooked lines of one color in the squares 10 which have previously received a ground coat. The next block, 7, also prints crooked lines by means of

its surfaces 7a in another color in the squares 10.

When the floor covering has moved from under the block 7, it has the appearance shown 5 in Figure 3, having an all-over pattern in contrasting colors with colored lines in those areas 10 of one color. So much of the process is old and is now commonly practiced, and the product shown in Figure 3 is what is at the 10 present time the nearest representation of a marble surface obtainable.

According to our invention, the linoleum next passes under the head 8, at which time 15 of course the paint is still wet. The block 8 has surfaces 8a adapted to cover the surfaces 10 of the printed linoleum, and the surfaces 8a, instead of being sawed, are entirely 20 smooth. The result is that when these surfaces press the wet paint in the squares 10 with the different colored lines thereover, and then lift away therefrom, the paint is smeared, the contour of the different colored 25 lines obliterated, and the paint left in a rough, unevenly distributed film in the squares 10, as shown in Figure 4.

Then, with the paint still wet, the web moves under the masher block 9 having sawed 30 surfaces 9a similar to block 4, but no paint is applied to this block. When the sawed surfaces 9a, which are adapted to cover the previously mutilated surfaces 10, press against these surfaces, the paint is smoothed down 35 and evenly distributed, but the curved lines are irregularly blended into the background and into one another, no longer having any 40 resemblance to lines. Instead of being of uniform shade, the paints are blended at some points more than at others, producing delicate shade variations and giving a mottled or stippled effect heretofore not procurable in printing processes of this kind. The 45 smearing of the paint by the block 8 and the subsequent redistribution by the block 9 will not be uniform, so that there will be no repeat of the pattern, thereby still further improving the product.

Besides producing an article which is 50 highly superior from an ornamental standpoint, there is a further advantage obtained by blending the design into the ground color. Where the colored lines are on the surface of 55 the ground color, the colored lines will wear off before the ground color, leaving no ornamentation thereon. By blending the colors into the ground color in this manner, the pattern is just as lasting as the ground color into which it is blended.

While we have described the invention in 60 connection with a printing machine, it will also be understood that we do not limit ourselves to machine printing in any step of the process or to the number and arrangement of colors used, the foregoing description being 65 merely illustrative of the invention, and vari-

ous changes and modifications may be made within the scope of the following claims.

We claim:

1. The method of printing floor coverings which consists in first applying a ground coat of paint to at least a portion of the surface of the floor covering, printing a well defined pattern over a portion of the area first coated, then pressing a solid smooth surface against that portion of the floor covering which has been thus printed, and then pressing a smooth block having a divided surface thereagainst. 70 75

2. The method of printing floor coverings which consists in applying a surface coat of paint to at least a portion of the surface of the floor covering with a printing block having a smooth divided surface, then printing a definite pattern over a portion of said first 80 85 coated area, then pressing a smooth solid surface against that portion to which the said surface coat and pattern have been applied, and finally pressing a smooth divided surface against that portion of the floor covering.

3. The method of decorating an area of 90 floor covering which consists in applying a surface coat of paint thereto, printing a definite pattern thereon with a printing block while the surface coat is wet, pressing a smooth solid surface thereagainst while the 95 paint remains wet, then pressing the surface with a smooth masher block having a finely divided surface.

4. In a machine for printing floor coverings, a series of reciprocable blocks beneath 100 which goods to be printed are passed, some of the blocks having sawed printing surfaces thereon, one of the blocks having smooth pressing surfaces thereon, and another block having a sawed smoothing surface thereon, 105 the block with the smooth pressing surface being intermediate some of the blocks having sawed printing surfaces and the block having the sawed smoothing surface.

5. In a machine for printing floor coverings, a series of reciprocable blocks beneath 110 which a piece of linoleum is adapted to be moved, one of the blocks having a sawed printing surface for producing a flat spread of color over a portion of the goods, a succeeding block having printing surfaces with a definite pattern, which pattern is positioned to be applied to the surface covered by the first mentioned block, still another succeeding block having a smooth projection thereon adapted to cover the area printed by the first mentioned block, and a succeeding finishing block having a sawed smoothing surface adapted to cover the area which the block having the smooth projections covers. 115 120

6. The combination with a printing machine for floor coverings and the like having a plurality of reciprocable printing heads, of printing blocks adapted to cover the surface 125

of a floor covering material with paint, a
block having a printing surface for applying
to such paint surface a predetermined over-
lying pattern, a block having a surface po-
sitioned to engage the applied pattern and
5 mutilate at least a portion thereof, and a
block adapted to engage the mutilated sur-
face and thereby blend the same with the
overlying paint.

10 In testimony whereof we have hereunto set
our hands.

CHARLES F. HUMPHREYS.
